UNITED STATES PATENT OFFICE.

CHARLES J. BAILEY, OF NEWTON, MASSACHUSETTS.

OVERSHOE.

SPECIFICATION forming part of Letters Patent No. 432,967, dated July 29, 1890.

Application filed May 20, 1890. Serial No. 352,442. (No model.)

To all whom it may concern:

Be it known that I, CHARLES J. BAILEY, of Newton, county of Middlesex, State of Massachusetts, have invented an Improvement in 5 Overshoes, of which the following description, in connection with the accompanying drawings, is a specification, like letters on the drawings representing like parts.

This invention has for its object to improve 10 the construction of overshoes, whereby they may be more securely retained upon the foot and be kept in shape at the instep.

I have shown my invention as embodied in 15 that class of overshoe known as "sandal" or "foot-hold."

Figure 1 in top view shows an overshoe containing my invention; Fig. 2, a section thereof.

In accordance with my invention I have provided an overshoe or sandal A, which may 20 be of any usual shape or material, with a tubular projection or rib B, which is located inside the shoe at the end of that part of the sole which terminates between the ball and instep.

The projection B in the sandal-shoe shown 25 in the drawings is extended across the inner end of the sole A' and is carried up along the inner side of the shoe to form a stay as well as a projection to aid in keeping the shoe on the foot.

30 I have found by experiment that the projection or rib when made as a tube will better engage the shoe over which it is fitted, for a

tube has greater elasticity than a solid rib, and, further, the tubular structure of the projection enables it to "give" to an obstruction 35 on the pavement or ground and making the shoe more comfortable, especially when worn over a very thin boot. The tubular projection is also of great utility, inasmuch as it is very effective in preventing the entrance of 40 mud and water into the overshoe to contact with the sole of the shoe on the foot.

The projection when made tubular acts after the manner of an elastic packing or cushion and very differently from what it would 45 act if a solid rib, which is not claimed.

I claim—

1. An overshoe provided at its interior with a transversely-tubular projection at the rear of the ball of the shoe, as and for the purposes 50 set forth.

2. The combination, with the sole and side walls of an overshoe, of the tubular projection attached to the inner portion of the said sole and extended upwardly along and secured to 55 the interior of the side walls, as and for the purpose set forth.

In testimony whereof I have signed my name to this specification in the presence of two subscribing witnesses.

CHARLES J. BAILEY.
